(57) **CLAIM**

The ornamental design for a handheld antenna mount, as shown.

DESCRIPTION

FIG. 1 is a front top perspective view of a handheld antenna mount, showing our new design;

FIG. 2 is a front top perspective view thereof with an attached antenna shown in broken lines;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines in the figures illustrate portions of the handheld antenna mount that form no part of the claimed design.
